ENGLAND.

APPARATUS FOR ORE CONCENTRATION.

1,155,815.

Specification of Letters Patent.

Patented Oct. 5, 1915.

Application filed November 12, 1913. Serial No. 800,441.

To all whom it may concern:

Be it known that we, ARTHUR HOWARD HIGGINS and WILLIAM WARWICK STENNING, both subjects of the King of England, and 5 residing at London, England, have invented certain new and useful Improvements in Apparatus for Ore Concentration, of which the following is a specification.

This invention is for improvements in or 10 relating to apparatus for ore concentration.

The apparatus is intended for carrying out the agitation froth process as described for example in previous United States Patents No. 835,120, to Sulman, Picard & Ballot, 15 of November 6, 1906, No. 962,678 to Sulman, Greenway & Higgins, of June 28, 1910, and No. 1,064,723 to Greenway & Lavers, of June 17, 1913, and also for carrying out the process of differential flotation as described 20 for example in previous United States Patent No. 1,067,485 to Nutter & Lavers, of July 15, 1913.

Hitherto it has been the common practice to introduce the ore pulp (with the agents 25 necessary for froth formation) into an agitation vessel where the pulp was subjected to violent agitation accompanied by the beating in of the supernatant air after which the pulp (containing a potential froth) was discharged into a separate spitzkasten in which 30 the froth floated and was separated.

One object of this invention is to provide 35 an apparatus in which agitation, aeration, froth formation and froth separation are effected in one box or series of boxes without requiring the use of spitzkasten.

A further object is to remove the froths 40 immediately they are formed so that a mineral-bearing froth ready for flotation shall not be subjected to further agitation with the pulp.

An incidental object is to effect the efficient recovery of so-called "tender" froths 45 from which the mineral has a tendency to shower.

An apparatus for concentrating ores by 50 gaseous flotation of certain mineral particles in liquid according to this invention comprises the combination with an upright vessel 55 having means for introducing an ore pulp and means for withdrawing residues (preferably at or near the bottom), of means for introducing air or other gas at or near the bottom of the vessel, means for violently 60 agitating and aerating the pulp near the bot-

tom of the vessel, means for maintaining the pulp comparatively still near the top of the vessel and means for removing mineral-bearing froth from the top of the vessel.

One practical form of the apparatus comprises the combination of an upright vessel (preferably rectangular) having an inlet for ore pulp and an outlet for residues, a horizontal centrifugal agitator near the bottom of the vessel, an air inlet pipe leading into the bottom of the vessel below the agitator and one or more baffles above the agitator so arranged as to provide a comparatively quiescent zone near the top of the vessel where the froth forms and is separated. 65

If desired the top of the vessel or vessels 70 may be constricted so as to conduct the froth to a comparatively small outlet at the top. The constricted portion may, if desired, be provided with baffles. This arrangement 75 may especially be employed where the mineral has a tendency to fall out of the froth.

The air inlet is preferably at the center of 80 the bottom of the vessel so that the air is drawn in by the rotation of the agitator, but the air inlet may be eccentric or a jet of air may be blown in at the bottom in such a way as to assist agitation, or the air may be introduced by a steam injector.

The accompanying drawing is a diagram 85 in perspective illustrating by way of example one method of carrying this invention into effect.

A preliminary mixing box A is provided 90 with an agitator B carried on a rotatable vertical spindle B¹. At the top is a conduit C for the introduction of ore pulp and vessels D provided with taps D¹ for the introduction of froth-forming agents such as oil, acid, etc. Connected to the center of the bottom of the box and below the agitator is an air inlet conduit E. The outlet for the pulp is a slot F in the discharge side of the box, partly covered by a plate F¹. The preliminary mixer as a matter of fact, may be of 95 any convenient form and forms no part of this invention. For example, it may be replaced by any other form of mixing apparatus with or without aeration or by a grinding apparatus operated as described in previous United States Patent No. 1,102,874, to George A. Chapman, issued July 7, 1914.

The frothing apparatus proper comprises 100 a series (say 8) of contiguous rectangular vessels G, G separated from one another by 105

partitions H. Each vessel has an air inlet pipe E leading to the center of the bottom of the vessel. A horizontal rotatable agitator B is arranged near the bottom of each vessel mounted on a vertical rotatable spindle B¹. The inlet for pulp to each vessel is the slot F which is partly covered by the directing plate F¹. At the right-hand side of the figure, the plate F¹ is shown broken away so as to make the form of the inlet conduit F more clear. The agitator may be a Howard agitator as described in United States Patent No. 1,084,210, issued January 13, 1914, or a plain four-blade agitator as shown at B² on the right-hand side of the figure or any other arrangement for producing violent turbulence can be employed and such device is hereinafter referred to as the centrifugal agitator.

Above the agitator and inclined downwardly from the inlet side to the outlet side is a baffle J which confines the violent turbulence mainly on its underside and which extends completely down to the outlet side but not completely up to the inlet side. The spindle B¹ passes through this baffle.

A second baffle K is arranged above the first baffle and is inclined downward a short distance from the inlet side of the vessel. The two baffles may if desired be spaced apart by divisions L, or a number of divisions in the form of a grid L¹ may be provided between the two baffles. Above these baffles the space in the vessel constitutes a quiescent zone where the froth forms, and a launder M is provided to catch the froth which passes over the overflow lips N of the vessels. Above the lowest point of the baffle J an outlet conduit is formed to lead the residues into the next vessel. This is the conduit F already described. The object of the curved directing plate F¹ is to insure that the action of the centrifugal agitator shall tend to draw in the pulp from the precipitating vessel and not to drive it back.

The operation of the apparatus is as follows:—The ore pulp containing the agents necessary for froth formation enters the first vessel G through the inlet conduit F, and the deflecting plate F¹ directs the flow of pulp as required. The centrifugal agitator B is rotated at a very high speed, say 1200 revolutions per minute, and the pulp is subjected to violent agitation. One action of the agitator is to draw in air through the air inlet pipe E and this air serves for the aeration of the pulp upon which the subsequent froth formation depends. The whole of the pulp passes upwardly under the inclined baffle J and meeting the upper baffle K, is deflected down on the upper side of the baffle J (thus for example the agitated and aerated pulp may come through the openings of the grids L¹). At this stage the pulp is comparatively still and the min-

eral-bearing froth forms and floats and escaping over the lip N of the vessel, falls into the launder M whence it is removed. The remaining pulp, containing the residues which fall down to the lowest point above the baffle J, passes through the slot F into the next vessel, where the same process is repeated, and finally from the last box the outlet F or its equivalent leads the residual pulp to the tailings receiver.

Although one of the main objects of the apparatus above described is to avoid the use of spitzkasten, it is to be understood where for example a very coherent froth is produced, with a tendency to include gangue, one or more spitzkastens may be employed in place of the launder M, for example a continuous open spitzkasten may be used as described in the previous United States patent to Broadbridge and Howard No. 1,084,196, issued January 13, 1914.

It will be seen that the single unit of the ore concentration apparatus embodying this invention consists of a vessel in which there is an inlet for air or other gas near the bottom, a zone of violent aeration and agitation near the bottom and a comparatively quiet zone near the top where the mineral-bearing froth forms and is separated. It is within this invention to vary the means for introducing air, the form and nature of the means for producing the violent agitation and aeration, the form and nature of the baffles or other means for creating a comparatively quiet zone distinct from the zone of turbulence, and the means for introducing the pulp and removing the froth and the residue.

What we claim as our invention and desire to secure by Letters Patent is:—

1. Apparatus for concentrating ores by gaseous flotation of certain mineral particles in liquid comprising, in combination, a vessel, means for introducing a gas therein at the lower part of the vessel, means for producing a zone of violent agitation and gassification in the lower part of the vessel, a baffle above the agitator for producing a quiescent zone in the upper part of the vessel, the baffle being inclined downwardly from the inlet side to the outlet side of the vessel, an inlet for the pulp to the vessel below the baffle, means for removing the froth from the upper surface of the liquid, and an outlet for the residues above the baffle.

2. Apparatus for concentrating ores by gaseous flotation of certain mineral particles in liquid comprising, in combination, a vessel, means for introducing a gas therein at the lower part of the vessel, means for producing a zone of violent agitation and gassification in the lower part of the vessel, a baffle above the agitator for producing a quiescent zone in the upper part of the ves-

- sel, the baffle being inclined downwardly from the inlet side to the outlet side of the vessel, a second baffle to direct the agitated and gasified pulp into the quiescent zone above the first mentioned baffle, an inlet for the pulp to the vessel below the baffle, means for removing the froth from the upper surface of the liquid, and an outlet for the residues above the baffle. 5
- 10 3. Apparatus for concentrating ores by gaseous flotation of certain mineral particles in liquid comprising, in combination, a series of contiguous vessels each having means for introducing a gas therein at the lower part of the vessel, means for producing a zone of violent agitation and gasification in the lower part of the vessel, a baffle above the agitator for producing a quiescent zone in the upper part of the vessel, the baffle being inclined downwardly from the inlet side to the outlet side of the vessel, an inlet for the pulp to the vessel below the baffle, means for removing the froth from the upper surface of the liquid, and an outlet for the residues above the baffle, the inlet to each vessel except the first of the series being also the residues outlet of the next contiguous vessel in advance. 15
- 20 4. Apparatus for concentrating ores by gaseous flotation of certain mineral particles in liquid comprising, in combination, a series of contiguous vessels each having means for introducing a gas therein at the lower part of the vessel, means for producing a zone of violent agitation and gasification in the lower part of the vessel, a baffle above the agitator for producing a quiescent zone in the upper part of the vessel, the baffle being inclined downwardly from the inlet side to the outlet side of the vessel, a second baffle to direct the agitated and aerated pulp into a quiescent zone above the baffle where the froth forms, means to remove the froth and an outlet for the residues above the baffle at its lowest point. 25
- 25 5. Apparatus for concentrating ores by gaseous flotation of certain mineral particles in liquid, comprising in combination an upright angular vessel, an air inlet pipe leading to the center of the bottom of the vessel, a centrifugal agitator near the bottom of the vessel, a baffle above the agitator and inclined downwardly from the inlet side to the outlet side of the vessel, an inlet for the pulp to the vessel below the baffle, a second baffle to direct the agitated and aerated pulp into a quiescent zone above the baffle where the froth forms, means to remove the froth and an outlet for the residues above the baffle at its lowest point. 30
- 30 6. Apparatus for concentrating ores by gaseous flotation of certain mineral particles in liquid, comprising, in combination, a series of contiguous angular vessels each of which has an air inlet pipe leading to the center of the bottom of the vessel, a centrifugal agitator near the bottom of the vessel, a baffle above the agitator and inclined downwardly from the inlet side to the outlet side of the vessel, an inlet for the pulp to the vessel below the baffle, a second baffle to direct the agitated and aerated pulp into a quiescent zone above the first baffle where the froth forms, means to remove the froth, the inlet to each vessel except the first of the series being also the residues outlet of the next contiguous vessel in advance and being located above the first baffle in such advance vessel and at the lowest point of such baffle, and a residues outlet for the last vessel of the series above the first baffle thereof at its lowest point. 35
- 35 7. Apparatus for concentrating ores by gaseous flotation of certain mineral particles in liquid comprising, in combination, a series of contiguous vessels each having means for introducing a gas therein at the lower part of the vessel, means for producing a zone of violent agitation and gasification in the lower part of the vessel, a baffle above the agitator for producing a quiescent zone in the upper part of the vessel, the baffle being inclined downwardly from the inlet side to the outlet side of the vessel, a second baffle to direct the agitated and gasified pulp into the quiescent zone above the first mentioned baffle, an inlet for the pulp to the vessel below the baffle, means for removing the froth from the upper surface of the liquid, and an outlet for the residues above the baffle, the inlet to each vessel except the first of the series being also the residues outlet of the next contiguous vessel in advance. 40
- 40 8. Apparatus for concentrating ores by gaseous flotation of certain mineral particles in liquid comprising, in combination, a series of contiguous vessels each having means for introducing a gas therein at the lower part of the vessel, means for producing a zone of violent agitation and gasification in the lower part of the vessel, a baffle above the agitator for producing a quiescent zone in the upper part of the vessel, the baffle being inclined downwardly from the inlet side to the outlet side of the vessel, a second baffle to direct the agitated and aerated pulp into a quiescent zone above the baffle where the froth forms, means to remove the froth, the inlet to each vessel except the first of the series being also the residues outlet of the next contiguous vessel in advance and being located above the first baffle in such advance vessel and at the lowest point of such baffle, and a residues outlet for the last vessel of the series above the first baffle thereof at its lowest point. 45

In testimony whereof we have signed our names to this specification in the presence of two subscribing witnesses.
